LIQUID DISCHARGE APPLIANCE

Frederick Alan Campbell, Langley, England, assignor of one-half to Fisher & Ludlow Limited, Birmingham, England

Application September 27, 1941, Serial No. 412,591
In Great Britain November 22, 1940

2 Claims. (Cl. 299—57)

This invention relates to a liquid discharge appliance of the kind wherein the liquid passes through a plurality of tubes which can be extended telescopically by hydraulic pressure.

The appliance is primarily intended for fire-fighting but it can be used for horticultural purposes or for spraying buildings.

The object of the present invention is to provide a form of apparatus whereby a discharge of liquid at a high level can be obtained in a minimum of time and with a minimum of effort.

A further object of the present invention is to provide a device which can be cheaply manufactured and assembled mainly from lengths of standard section tube.

Referring to the drawing:

Figure 1 is a view in side elevation showing one form of the apparatus with the liquid discharge tubes in their contracted and lowered position.

Figure 2 is a plan view.

Figure 3 is a view in side elevation showing the liquid discharge tubes in the contracted but raised position.

Figure 4 is a sectional view on line 4—4 of Figure 3.

Figures 5 and 5A constitute a view in section taken through the main liquid discharge tubes showing them in the contracted position.

Figure 6 is a sectional view showing one end of the primary tube and the adjacent end of the secondary tube engaging therein in the extended position.

In the construction illustrated the liquid discharge appliance is shown mounted upon the chassis 10 of a vehicle supported on road wheels 11 and having at the front a traction element 12 pivoted on a horizontal axis as shown at 13. The traction element is provided with a lever 14 whereby the usual automatic brake used with trailer vehicles can be operated. The vehicle shown is a trailer vehicle and is provided with a towing eye 15.

In the construction shown the front axle 92 of the vehicle is associated with a forecarriage 93 having a turntable 94 so that the forecarriage can turn relatively to the vehicle frame.

The element 12 is provided with a pair of bars 95 pivoted on butt hinges 96. These bars are foldable into the positions shown in chain dot lines or they can be moved forwardly to the position shown in full lines. These bars are for use in manoeuvring the vehicle manually after it has been detached from the tractor vehicle.

At the rear part of the vehicle and projecting

upwardly therefrom is a bracket comprising two vertical members 16 suitably secured at the base and two inclined members 17 secured to the base at 18. Each member 16 is secured to one of the members 17 at the top by welding.

A cradle consisting of four channel section members 20, 21, 22 and 23 and a connecting tube 35 is pivoted on the cross shaft 19 which passes through bearings on the upper ends of the members 16. Further, oblique stays 24 extend between the tube 35 and the end of the member 20 remote from the tube 35 and further oblique stays 25 extend between the tube 35 and the end of the member 22 which is remote from the tube 35.

The four members 20, 21, 22 and 23 are all of channel section and the stays 24 and 25 may be of angle section or any other section that may be desired.

The bracket members 16 and 17 are shown as being of angle section but they may be of any other cross sectional shape that may be desired.

The underside of the member 23 is open and pivotally mounted therein on trunnions 26 is a block 27 which is screw threaded internally. Engaging in the block 27 with its external thread is a hollow strut member 28. Within the lower end of the strut member is fixed a nut 29 in which screws a rotatable strut member 30 having a head 31.

The lower end of the strut member 30 carries a bevel wheel 32 which is engaged by bevel wheels 33 mounted on the operating shaft 34 provided on the vehicle.

On the upper surface of the vehicle two angle section members 36 are provided. These extend across the chassis frame and they carry two pairs of bearings 37 in which the shaft 34 can rotate.

Pivoted between the two adjacent bearings 37 is a gear box 38 containing the bevel gearing 32, 33. This gear box may be pivoted by means of trunnions in the two adjacent bearings 37.

The shaft 34 is provided with end portions 39 which can be engaged by a removable crank 40 so that the rotatable strut member 30 may be operated from either side of the appliance to extend the strut.

Normally the strut member 30 rotates and the strut member 28 does not rotate but moves axially in relation to the member 30 to extend the strut. When the head 31 of the strut member 30 comes into contact with the end of the nut 29, further rotation of the strut member 30 also drives the strut member 28 causing it to turn in

the block 27 and thus continue the extension of the strut until the position shown in Figure 4 is reached.

The member 20 of the cradle is used to carry the primary tube 41 of the appliance. The member 20 is provided with a pair of seatings 42 engaged by the tube 41 and the tube is secured by external straps 48 attached to the seatings.

At its lower end the tube is provided with an inlet fitting 44 having a shank 45 to which a hose may be attached. Preferably the hose is provided with its own stop valve so that the flow of liquid pressure may be controlled thereby.

The fitting 44 is provided with a valve seat 46 on which operates a non-return valve 47 the stem of which is provided with a shock absorbing spring 48.

The pressure of the incoming liquid opens the valve and the valve prevents any back flow of liquid.

The tube 41 can be a length of standard construction tube and it has welded to its lower end a flange 49 which is bolted to the flange 50 of the inlet fitting 44 with suitable packing intervening.

At its outer end the tube 41 has a flange 51 welded to it and it is provided with two stuffing box members 52, 53 which can be drawn together by means of bolts 54.

The bolts 54 carry nuts 55 which are used to secure the stuffing box element 52 to the flange 41 with suitable intervening packing.

The stuffing box element 52 is provided with a skirt 56 having two V-shaped notches 57.

Further, the primary tube 41 is provided with two groups 58 and 59 of openings which are placed between two rings 60 secured to its exterior and secured to the peripheries of the rings 60 is a sleeve 61, the space within this sleeve forming part of the transfer passage of the primary tube.

The secondary tube is shown at 62 and at its inner end it is fitted with a piston 63 engaging the internal wall of the tube 41. The piston 63 may be made of metal and one side of it 64 is of cup-like construction receiving the end of the tube 62 while the other side of it is provided with a flange 65 in which there may be a number of radial saw cuts for the purpose of making the flange somewhat resilient. Further, the piston may have an external groove as shown at 66 also for the purpose of increasing the resilience of the part 65.

Near the end where the piston is secured the secondary tube 62 is provided with a group of openings 67.

The exterior of the secondary tube has fixed to it a collar 68 on which are a pair of projections 69 adapted to co-operate with the notches 57 when the secondary tube is extended.

The appliance may be provided with a discharge device 70 or other discharge orifice which may be of any known construction. If the appliance comprises only the primary and secondary tubes then the discharge device 70 may be secured to the outer end of the secondary tube but in the construction shown there is a third tube 71 and the discharge device is applied to the outer end thereof.

As there is a third tube in the construction illustrated, the secondary tube at its outer end is provided with stuffing box elements which are similar to those described in connection with the outer end of the primary tube and are shown at 77 and 78. These stuffing box elements can

be drawn together by means of bolts 79 provided with nuts 80 so that the element 77 can be bolted to the flange 81 welded to the end of the secondary tube.

Further, the secondary tube is also provided with two groups of openings which correspond to the openings 58 and 59 of the primary tube. The groups of openings in the secondary tube are shown at 72 and 73 respectively and they are enclosed by a sleeve 74 secured to the peripheries of two rings 75 and 76 secured to the exterior of the secondary tube.

The inner end of the third tube 71 is provided with a piston 82 which is constructed similarly to the piston 63 but differs from it in that it is provided with a small hole 83. The purpose of providing this hole is to allow the liquid in the third tube 71 to drain into the secondary tube when it is desired to allow the appliance to contract. If this hole 83 were not provided it would be necessary to provide other means for draining away the liquid in the third tube.

The primary tube is provided with a primary drain pipe 84 having a cock 85 and a secondary drain pipe 86 having a drain cock 87. The provision of the secondary drain pipe and cock is necessary because there is no opening in the piston 63.

The third tube 71 is provided with a collar 88 having projections 89 which co-operate with the notches 90 in the skirt 91 of the stuffing box element 77 on the end of the secondary tube thus preventing the third tube from turning on its own axis when extended.

The third tube 71 is, of course, guided and supported in the secondary tube 62 by the piston 63 and the stuffing box elements 77 and 78.

The three telescopic tubes are moved and retained in their extended position by the water pressure entering at 45, the pressure acting on the underside of the piston 63 and moving it into the position shown in Figure 6. The liquid then flows through the ports 58 and the transfer passage within the sleeve 61 and the ports 67 into the secondary tube and acts upon the underside of the piston 82 causing it to slide outwardly until the ports 92 in the third tube receive the liquid from the transfer ports 73 in the secondary tube. The liquid then passes upwardly along the third tube 71 until it reaches the discharge device 70.

When it is desired to contract the apparatus the stop valve associated with the hose is closed and the drain cocks 85 and 87 are opened.

After it has been contracted the apparatus can be lowered on the vehicle by operating one of the shafts 34 or 35.

What I claim is:

1. A liquid discharge appliance comprising a plurality of telescopically extensible tubes, including a primary tube having a liquid inlet connection, a non-return valve and a discharge cock, a secondary tube slidably mounted in the primary tube, a piston on the end of the secondary tube within the primary tube and engaging the wall of the primary tube, and a stop for limiting outward sliding movement of the secondary tube due to pressure of liquid in the primary tube acting on the piston, said primary tube having a transfer port uncovered by the piston when the secondary tube is fully extended, said transfer port being formed by providing at least two axially spaced openings in the wall of the primary tube, a pair of rings on the exterior of the

said tube, one ring being fixed thereto at one side of both openings, and the other ring being fixed thereto at the opposite side of both openings, a sleeve secured to the peripheries of the two rings, said secondary tube having a liquid inlet port in its side, said transfer port communicating with said liquid inlet port when the secondary tube is fully extended so that liquid pressure on the piston then keeps the secondary tube fully extended and liquid then flows through the transfer port and liquid inlet port into the secondary tube, said secondary tube having a liquid discharge orifice.

2. A liquid discharge appliance comprising a plurality of telescopically extensible tubes, including a primary tube having a liquid inlet connection, a non-return valve and a discharge

cock, near one of its ends, and a stuffing box at its opposite end, a piston on the end of the secondary tube within the primary tube and engaging the wall of the primary tube, said secondary tube being guided in its sliding movements by its piston in the primary tube and by its engagement with the stuffing box, a collar on the secondary tube co-acting with the stuffing box to form a stop to limit the outward sliding movement of the secondary tube, a skirt on the stuffing box, and an inclined sided projection on the collar and a correspondingly shaped notch in the skirt of the stuffing box for positioning the secondary tube angularly around its axis when fully extended.

FREDERICK ALAN CAMPBELL.
